DESIGN FOR A BOOK END

James G. Kaufman, Stockton, Calif.

Application March 25, 1940, Serial No. 91,496

Term of patent 14 years

To all whom it may concern:

Be it known that I, James G. Kaufman, a citizen of the United States of America, residing at Stockton, in the county of San Joaquin and State of California, have invented a new, original, and ornamental Design for a Book End, of which the following is a specification, reference being had to the accompanying drawing, forming a part thereof.

I claim:

The ornamental design for a book end, as shown.

JAMES G. KAUFMAN,
